MULTIPLE CONTACT ELECTRICAL CONNECTOR ASSEMBLY

Richard E. Brown, Gahanna, Ohio, assignor to Twyco, Inc., Blacklick, Ohio

Filed Oct. 22, 1971, Ser. No. 191,970

Term of patent 14 years

Int. Cl. D13—03

U.S. Cl. D26—1 A

FIG. 1 is a perspective view of a multiple contact electrical connector assembly embodying my design.

FIG. 2 is a horizontal sectional view taken along line 2—2 of FIG. 1.

FIG. 3 is a horizontal sectional view taken along line 3—3 of FIG. 1.

FIG. 4 is a bottom edge view of the connector assembly.

FIG. 5 is a vertical sectional view taken along line 5—5 of FIG. 1.

I claim:

The ornamental design for a multiple contact electrical connector assembly, substantially as shown.
